BOILER-ALARM.

1,203,979.

Specification of Letters Patent. Patented Nov. 7, 1916.

Application filed February 8, 1912. Serial No. 676,296.

To all whom it may concern:

Be it known that we, CHARLES MOTLEY CLARK and ROGER W. ANDREWS, citizens of the United States, residing at Chicago, in the county of Cook and State of Illinois, have invented certain new and useful Improvements in Boiler-Alarms, of which the following is a specification.

This invention relates to boiler alarms which sound a whistle or other alarm when the water in the boiler becomes either lower or higher than is desired.

One of the objects of the invention is to produce a device which depends for its action directly upon the height of the water in the boiler, and which does not depend upon a float or a diaphragm. It has been found that floats, especially when used with high pressure boilers, become water-logged in time and are also likely to be affected by substances in the water adhering to the float itself, or to other portions of the float device. It has also been found that diaphragms are affected by the high temperature involved in high pressure boilers. And both the float and the diaphragm structures are necessarily inclosed within the boiler, or some adjacent chamber, so that they are not easily accessible. And the object of this invention is not only to avoid the use of the float and the diaphragm, but it is also to place the device entirely in the open where it is accessible either for adjustment or repairs.

A further object of the device is to provide an alarm which is certain in its action. The operative portion of the device depends upon the expanding and contracting of metal tubes when heated or cooled, the force developed thereby being practically irresistible. The operation of the alarm is thus much more certain than where the force depends upon the buoyancy of a float, or even the pressure of the steam acting upon the diaphragm.

The device consists of a duplex thermostat comprising two expansion and contraction tubes. Normally one of these tubes is filled with water and the other with steam, and the tubes are so arranged and connected with the boiler that when the water in the boiler sinks below what is called its minimum water level, steam replaces the water in one tube, the tube is expanded, and the

whistle valve opened. As soon as the water in the boiler again rises up to its minimum water level, the water replaces steam in the tube, the tube is contracted, and the whistle valve is closed. On the other hand, when the water in the boiler rises above its maximum water level, water passes into the other tube replacing the steam, the tube contracts, and the steam valve is opened. And, when the water in the boiler sinks to its maximum water level, steam replaces water in the tube, the tube expands, and the whistle valve is closed. By minimum and maximum water levels we refer respectively to the lowest and highest levels that it is desired to have the water go normally without sounding the alarm.

In order to attain these objects we may use mechanism similar to that illustrated in the accompanying drawings, in which—

Figure 1 is a front view of a thermostat and whistle. Fig. 2 is a vertical central section of the whistle valve. Fig. 3 is a plan view of the thermostat and whistle valve. Fig. 4 is a front view of the thermostat complete, including boiler connections. Fig. 5 is a modified form of a valve-controlling mechanism.

The thermostat 10 comprises a tube 11 and a tube 12. Tube 11 is composed of metal having a high coefficient of thermal expansion. Tube 12 may be composed of metal of a lower coefficient of expansion. The head 13 of the tube 12 is connected by means of a forked link 14 and a pivot 15 with one end of a lever 16. The head 17 of the tube 11 is pivoted directly to the lever 16. The other end of the lever 16 has an elongated opening 18 therethrough, through which projects the valve stem 19 of the valve 20 which admits steam to the whistle 21. Beneath the end of the lever 16 and threaded on to the valve stem 19 are nuts 22 by means of which the position of the lever with reference to the valve stem may be adjusted, the lower nut serving as a lock nut.

The other ends of the two tubes are threaded into the heel 23 of the thermostat. The whistle valve 20 is supported by an upright 24 which is threaded at one end into the thermostat heel and at the other end into the valve. A jointed brace 25 is slidably attached to the upright 24 by means of the set

screw 26, the outer end of the brace encircling the tubes 11 and 12 and being rigidly secured to the tube 12 by means of the set screw 27. The tube 11 is free to slide 5 through the opening in the brace, but is snugly held thereby.

Pipes 28 and 29 are threaded into the heel 23 of the thermostat, the pipe 28 being connected by means of the heel with the tube 11 10 of the thermostat, and pipe 29 being connected by means of the heel with the tube 12. Connection is made by means of a tube 30 between each of the tubes 28 and 29 and the lower end of a water trap 31. The upper 15 end of the water trap 31, which is positioned well below the minimum water level, is connected by means of a pipe 32 with the blow-off pipe 33 of the water column 34 of the boiler.

20 Pipe 11 of the thermostat is connected by means of its head 17 with the pipe 37 which is connected to the upper valve pipe 38 of the water column. Pipe 12 of the thermostat is connected by means of its head 13 25 with the pipe 35 which is connected with the lower valve pipe 36 of the water column. At suitable points in these various pipes are placed unions and valves. It should be understood that the connections to the boiler 30 may be made in any other suitable way, however; care being taken that the connections are at the maximum and minimum water level points.

Normally the water in the boiler stands 35 substantially level with the valve pipe 39 in the water column. The limits of safety range somewhat below the pipe 36 and somewhat above the pipe 38 of the water column. When the water in the boiler is within the 40 safety limits, the pipes 36, 35, 12, 29 and 30, and the water trap 31 are filled with water; while pipes 28 or the upper portion thereof, pipes 11, 37 and 38 are filled with steam; and the position of the thermostat lever is 45 such that the pressure of the steam entering the whistle valve through the pipe 39^a is enabled to hold the valve closed. The pipe 39^a may be connected with the boiler at any suitable place above the maximum water level.

50 When the water sinks in the boiler below the pipe 36, steam passes from the boiler into the pipes 36 and 35 allowing the water to flow therefrom, and also into the pipe 12 and the upper portion of the pipe 29, the 55 water in pipes 12 and 29 flowing downward into pipe 30 and the trap. The increased temperature of the steam which enters the pipe 12 causes this pipe to expand; the pivoted end of the lever 16 is forced upwardly, 60 the other end is forced downwardly, and the steam valve is pressed open by means of the valve stem 19, and the alarm sounds. If water is then passed into the boiler until it rises above the pipe 36, this will cut off from 65 the steam portion of the boiler pipes 35, 12

and 29. The steam contained in these pipes will quickly condense and the steam in the boiler will force water from the water column, and from the steam trap and the pipes below the thermostat, upward to replace the 70 condensed steam. The water rising in the pipes 29 and 12 on the one hand and in the pipe 35 on the other hand will rise substantially at the same rate, so that the water which enters from the boiler will not go beyond the upper bend in pipe 35, while that which enters tube 12 will come from the pipe 30 or the trap 31, and will be at a much lower temperature than the water in the boiler. The tube 12 will be cooled, it will contract, 75 and will draw downwardly the pivoted end of the lever 16 and allow the steam to force into its seat the face of the whistle valve 20, and the alarm will cease.

If the water in the boiler rises above the 80 pipe 38, steam in the pipe 37 and the tube 11 will be cut off from the boiler and will quickly condense. The water will then rise in these tubes, pressed upward by the boiler steam pressure, and for the same reason as 85 stated with reference to tube 12, cool water from the tube 30 will enter the tube 11 and meet the hot water from the boiler at the upper portion of the bend of the pipe 37. Tube 11 will be cooled, will contract, the 90 inner end of the lever 16 will thus be forced downward, and the valve face will be unseated by the stem 19, and the whistle will sound. When the water in the boiler is lowered so that steam again has access to pipe 38, 95 steam will pass into pipe 37 and tube 11, and the contained water will flow down; that in pipe 37 passing into the water column, and that in tube 11 passing into the pipe 30 or the trap. Tube 11 will expand, the inner end of the lever will be forced upward, and the steam will close the valve, and the whistle will cease.

As indicated, the purpose of the steam trap 31 is to contain sufficient water so that 100 the thermostat tubes will always be filled with water which is at a much lower temperature than the boiler water. Although the trap is directly connected to the boiler, yet its capacity and the capacity of pipe 30 105 are such that the thermostat tubes are always filled with the water contained therein, the hot water from the boiler merely forcing the cool water from pipe 30 and the trap upward into the tubes. Also as indicated, 110 the bends in the upper ends of the pipes 35 and 37 are for the purpose of preventing hot water from the boiler passing into the upper ends of the thermostat tubes and thus fill, more or less, these tubes with hot water 115 at a temperature substantially the same as the temperature of the steam. In such a case it would be necessary for the tubes to radiate out more or less heat before the contraction would be sufficient to cause action 120 125 130 135

of the whistle valve. But by providing, by the means suggested, cool water for the tubes, the action of the tubes due to their contraction is almost instantaneous.

5 Valves 40 and 40^a are provided in the pipes 35 and 37 in order that the thermostat may be conveniently cut off from the boiler. If so desired, for any reason, these valves may also be used to form a constricted portion in the pipes 35 and 37. This will cause the water in these pipes to flow upward more slowly than in the tubes 11 and 12. Hence if the installation is such that hot water passes over the bends in the tubes 35 and 37 so as to more or less affect the rate of contraction of the tubes, these pipes, or either of them, may be constricted temporarily or permanently by means of the valves 40 and 40^a, and the hot water thereby 10 prevented from entering the thermostat tubes. Valve 40^a may also be used for the purpose of testing the whistle and the action of tube 11. By closing the valve, tube 11 and pipe 37 are cut off from the boiler, 15 and, if in proper condition, tube 11 will contract and the whistle will blow. Similarly valve 40^b may be used for testing the whistle and tube 12. When the valve is open, steam forces the water from tubes 20 35 and 12 of the thermostat into the trap through the valve and into the atmosphere, and the tube 12 expands causing the whistle to blow.

It will, of course, be understood that the 25 purpose of the lever 16 is to greatly multiply the movement of the free ends of the tubes 11 and 12 as either of the tubes expands or contracts. The slight motion of the ends of the tubes themselves due to the expansion 30 or contraction would be entirely insufficient to properly and certainly actuate the valve. And where certainty of action is the great essential, a large amount of excess motion must be provided for to take care of any 35 abnormal conditions that may arise.

It will be noticed that the tube 11 contracts and that tube 12 expands to cause the alarm to sound. It has been found in practice that the action of tube 12 under 40 similar conditions is much more rapid than that of tube 11. This is due to the fact that tube 12 is heated by the steam more quickly than tube 11 is cooled by the water. No 45 alarm is sounded usually until after a long period of time has elapsed, and hence the water in tube 12 becomes comparatively cool. As a result there is a considerable excess contraction of the tube. This causes the valve end of the lever to rise away from 50 the nut on the valve stem. As a consequence the water which fills tube 11 when high water occurs is likely to be considerably warmer than the water in tube 12, because it usually comes from a warmer location 55 and some water from the boiler itself may

mix in. And in addition, this water must contract the tube 11 sufficiently to offset the excess contraction of the tube 12 before any effective action can occur. Hence more or less time must elapse before the water cools 70 sufficiently to sound the alarm. To remedy this it is found desirable to materially favor the action of the contraction tube 11. This is done by making that tube somewhat longer than the other, giving it a greater 75 leverage ratio, and making tube 12 of less expansive material. The amount of contraction being in proportion to the length, the effect necessarily is quickened by lengthening the tube. By pivoting tube 11 to the 80 valve lever at the inner point the ratio of the valve arm to the tube arm is greater than the ratio of the valve arm to the tube arm in case of tube 12 with tube 11. Hence the action of tube 11 is correspondingly quickened. And finally, as the action of tube 11 85 is delayed by the excess contraction of the tube 12, decreasing the contractility of that tube necessarily quickens the action of tube 11. 90

It will be seen that excess contraction or expansion of either tube is fully cared for. An excess of expansion of tube 11 or contraction of tube 12 will cause the valve arm of the lever to move freely away from the 95 nut of the valve stem so far as may be necessary. And an excess contraction of tube 11 or expansion of tube 12 will cause the valve arm to sink and the valve face to be pushed downwardly so far as may be necessary into 100 the chamber 42.

The valve 20 is of special construction. As stated it is supported on the upright 24 which is threaded into the base of the valve. The steam enters through the pipe 39^a which 105 is at right-angles to this support. It has been found that in installing an apparatus of this nature it is desirable to be able to allow the steam to enter from different directions with reference to the position of 110 the thermostat. To provide for this it is necessary only to rotate the valve on its support, as the axis of the support and the valve stem coincide. By this means the steam may enter from substantially any direction 115 with reference to the plane of the thermostat.

In the interior of the valve a lug 41 is provided which projects a substantial distance below the inlet port 43 of the valve. 120 This lug serves two purposes. It has been found that steam entering the valve is much more effective in causing it to close if it strikes substantially at right-angles to the valve face, and with the construction shown, the steam is forced downward through the passage 44 into the chamber 42, and then moves upward directly at right angles to the face of the valve. This not only prevents any tendency of the valve stem to stick 125 130

because of side force acting on the valve, but eliminates entirely any tendency of any portion of the entering steam to keep the valve open causing practically all of the entering steam to tend directly to close the valve. This construction allows the valve to be used without any provision other than the steam itself for closing the valve, when at liberty to do so, by the rising of the arm 10 of the lever 16. The lug 41 also provides a chamber within the valve which is normally filled with water. Steam entering the valve from the boiler is condensed, flows into and remains in the chamber 42 until 15 the chamber, including the upper portion surrounding the valve face and seat, is entirely filled with water. As a consequence the life of the valve is greatly prolonged and repairs are much less needed for the 20 reason, first, that the contained water cools and keeps the valve parts in better condition to resist wear, and further for the reason that, as is well known, water in contact with the softer metals is much less injurious 25 than steam, steam having an eating tendency which is much greater than water, especially when the water is comparatively cool. The water also prevents leakage and keeps the parts in a moist condition so that action is 30 more rapid than when the parts are in contact only with dry steam. The valve therefore is especially adapted for use with an alarm of this nature which depends for its value altogether upon the certainty of 35 prompt action and which lies idle over long periods of time. A pin 42^a is set in the supporting rod 24, below the valve face to prevent the face from sinking too low when the steam pressure sinks or ceases altogether.

40 Fig. 5 shows a modified form of the valve-controlling mechanism. The lever 16^a acts directly upon the valve stem according to the action of the lever 16 hereinbefore described. But a second lever 45 is pivoted to 45 the upper end of the link 46 at the point 47, the link being pivoted to a projecting lug 48 of the valve casing. The valve stem 19^a, because of the steam pressure, presses against the lever 16^a, as with the other form, 50 and the weight 49 assists the steam pressure by forcing the inner end of its lever upward against the nuts 22^a. Normally the lever 16^a allows the weight 49 and the steam pressure to hold the valve closed. When 55 steam enters the tube 12 the tube expands, the inner end of the lever 16^a is forced downward; this raises the weight and forces the valve open. When the tube 12 contracts, again, the weight sinks and the valve is 60 closed. On the other hand, when tube 11 has its steam replaced by water, it contracts, the weight is raised and the valve is opened. When steam again enters the tube, the weight lowers and the valve closes. So that 65 the operation is similar to the operation

hereinbefore described with reference to the other form of mechanism, the weight merely making more certain the action of the valve. This modification is of special value when for any reason a stuffing box is used with 70 the valve, or when an ordinary valve is used. 75

An adjusting nut 50 may be placed on the whistle so that the tone of the whistle may be varied in order to make it distinguishable from other whistles, or for any other reason.

We wish it understood that we do not limit ourselves to the details of construction herein shown, for various modifications within the scope of the claims will occur to 80 those skilled in the art.

In the claims attached hereto, by the use of the expressions "contractible tube" and "expansible tube" we refer to tubes composed of materials which have a high coefficient of thermal expansion, the contractible tube being the tube which when contracting operates the valve, the expansible tube being the tube which when expanding operates the valve. 85 90

We claim as our invention:

1. A boiler alarm comprising a contractible tube, a conductor connected to one end of said tube, said conductor being adapted to be connected to a boiler at its maximum 95 water level, and a bend in said conductor extending above said tube; one end of said tube being rigidly supported, and the other end of said tube being adapted to actuate a device when said tube contracts. 100

2. A boiler alarm comprising an expansible tube, a conductor connected by one end to one end of said tube, the other end of said conductor adapted to be connected to a boiler at its minimum water level, said conductor having a bend extending above said tube, the other end of said tube adapted to be connected to the boiler below its minimum water level, one end of said tube being rigidly supported, and the unsupported end of 105 said tube adapted to operate a device when the tube expands. 110

3. A boiler alarm comprising a contractible tube and an expansible tube, a first conductor connected by one end with one 115 end of said contractible tube; said conductor adapted to be connected with a boiler at its maximum water level and having a bend therein above said contractible tube, a second conductor having one end connected to one end of said expansible tube, the other end of said second conductor adapted to be connected with the boiler at its minimum water level and having a bend therein above said expansible tube, the other ends 120 of each of said tubes being rigidly supported and being connected with a third conductor, said third conductor being connected with the boiler below its minimum 125 water level, a water trap in said third conductor 130

ductor, and the free ends of said tubes adapted to operate a device when said contractible tube contracts or said expansible tube expands.

5 4. A boiler alarm comprising a contractible tube, an expansible tube, and a lever, one end of said contractible tube adapted to be connected with a boiler at its maximum water level, one end of said expansible

10 tube adapted to be connected with the boiler at its minimum water level, one end of each of said tubes being rigidly supported, said tubes being composed of material of different coefficients of thermal expansion, the 15 free ends of said tubes being pivotally connected adjacent to each other near one end of said lever, the other end of said lever being adapted to be operatively connected to an alarm device.

20 5. A boiler alarm comprising metal tubes of unequal lengths, and a lever, said tubes being adapted to be connected with a boiler respectively at its maximum and its minimum water level, the other ends of said 25 tubes being adapted to be connected to said boiler below its minimum water level, one end of each of said tubes being rigidly supported, the other ends of said tubes being pivotally connected adjacent to each other 30 to one end of said lever, and the other end of said lever being adapted to be operatively connected to an alarm device.

6. A boiler alarm comprising a contractible tube and an expansible tube of unequal 35 lengths and of unlike coefficients of thermal expansion, one end of one of said tubes being adapted to be connected to a boiler at its minimum water level, one end of the other of said tubes being adapted to be connected 40 to said boiler at its maximum water level, one end of each of said tubes being rigidly supported, the unsupported ends of said tubes being pivotally connected adjacent to each other near one end of said lever, the 45 other end of said lever being adapted to be operatively connected to an alarm device.

7. The combination of a boiler, a device, and a boiler alarm, said alarm comprising two thermostatic tubes and a lever, one end 50 of one of said tubes being connected with the boiler at its maximum water level, one end of the other tube being connected with the boiler at its minimum water level, one end of each of said tubes being rigidly supported, the other ends of said tubes being pivotally connected to said lever adjacent one end, and the other end of said lever when operated by said tubes being adapted to actuate said device.

60 8. A boiler alarm comprising a contractible and an expansible tube, one end of said contractible tube adapted to be connected with the boiler at its maximum water level, one end of said expansible tube adapted to 65 be connected with a boiler at its minimum

water level, a conductor having one end connected to each of the other ends of said tubes, and the other end of said conductor adapted to be connected to a boiler below its minimum water level, and a water trap 70 in said conductor, one end of each of said tubes rigidly supported, the other ends of said tubes adapted to actuate a device when said contractible tube contracts or the expansible tube expands.

75 9. A boiler alarm comprising a contractible tube, a first conductor connected to one end of said tube, and a second conductor connected to the other end of said tube; said first conductor adapted to be connected to a boiler at its maximum water level, and a bend in said first conductor extending above said tube, said second conductor adapted to be connected with a boiler below its minimum water level, and a trap in said second 80 conductor below said minimum water level, one end of said tube rigidly supported, the other end of said tube when it contracts being adapted to control a device.

90 10. A boiler alarm comprising an expansible tube, a first conductor connected by one end to one end of said tube, the other end of said conductor adapted to be connected to a boiler at its minimum water level, and a bend in said conductor extending above said tube; a second conductor having one end connected to the other end of said tube, the other end of said second conductor adapted to be connected to a boiler below its minimum water level, and a trap in said second conductor, one end of said tube rigidly supported, and the unsupported end of said tube adapted to operate 95 a device when the tube expands.

100 11. A boiler alarm comprising a contractible tube and an expansible tube, a first conductor connected by one end with one end of said contractible tube, said conductor adapted to be connected with the boiler at its maximum water level, a bend in said conductor above said contractible tube, a second conductor having one end connected to one end of said expansible tube, the other end of said second conductor adapted to be connected with a boiler at its minimum water level, and a bend in said second conductor above 110 said expansible tube, the other ends of each of said tubes rigidly supported, and the free ends of said tubes adapted to operate a device when said contractible tube contracts 115 or said expansible tube expands.

12. A boiled alarm comprising a contractible and an expansible tube, and a lever, one end of said contractible tube adapted to be connected with a boiler at its maximum water level, one end of said expansible tube adapted to be connected with the boiler at its minimum water level, one end of each of said tubes rigidly supported, said expansible tube being composed of material of lower co- 125 130

efficient of thermal expansion than said contractible tube, the free end of said expansible tube pivotally connected to one end of said lever, the free end of said contractible tube pivotally connected to said lever adjacent to said lever end, the other end of said lever adapted to actuate a device, whereby when said contractible tube contracts or said expansible tube expands, said lever will operate said device.

13. A boiler alarm comprising a contractible tube, an expansible tube, and a lever, one end of said contractible tube adapted to be connected with a boiler at its maximum water level, one end of said expansible tube adapted to be connected with the boiler at its minimum water level, one end of each of said tubes rigidly supported, the free end of said expansible tube pivotally connected to one end of said lever, the free end of said contractible tube pivotally connected to said lever intermediate its ends, the other end of said lever adapted to actuate a device whereby when said contractible tube contracts or

said expansible tube expands, said lever will operate said device.

14. A boiler alarm comprising a contractible tube, an expansible tube, and a lever, one end of said contractible tube adapted to be connected with a boiler at its maximum water level, one end of said expansible tube adapted to be connected with the boiler at its minimum water level, one end of each of said tubes rigidly supported, the free end of said expansible tube pivotally connected to one end of said lever, the free end of the other tube pivotally connected to said lever intermediate its ends, and the other end of said lever when operated by said tubes being adapted to actuate a device.

In testimony whereof we affix our signatures in the presence of two witnesses.
